EDGAR PERCIVAL BIDWELL, OF LONDON, ENGLAND.

TOILET-CASE.

1,126,360.

Specification of Letters Patent.

Patented Jan. 26, 1915.

Application filed November 12, 1913. Serial No. 800,510.

To all whom it may concern:

Be it known that I, EDGAR PERCIVAL BIDWELL, a subject of the King of Great Britain, and a resident of London, England, 5 have invented a new and Improved Toilet-Case, of which the following is a full, clear, and exact description.

The invention relates to toilet accessories, and its object is to provide a new and improved toilet case more especially designed 10 for men's use and arranged to contain a large number of toilet articles in a comparatively small space thus rendering the dressing case exceedingly serviceable for the use 15 of travelers and other persons.

In order to accomplish the desired result use is made of a casing provided on the inner walls with retaining devices for removably holding toilet articles, such as a 20 razor, tooth brush, comb, a pair of scissors and a mirror, a hair brush held removably in the said casing, and a protecting band in the form of a razor strop and looped around the bristles of the said hair brush to protect 25 the bristles against the said loops and the toilet articles carried thereby. Use is also made of a drawer removably held in an opening in the back of the hair brush, the drawer being adapted to contain toilet articles 30 such as a shaving brush, a stick of shaving soap and a nail brush. The drawer when removed from the back of the brush permits the user to take a firm grip on the back for conveniently using the hair brush.

35 A practical embodiment of the invention is represented in the accompanying drawings forming a part of this specification, in which similar characters of reference indicate corresponding parts in all the views.

40 Figure 1 is a perspective view of the dressing case with the cover thereof in open position; Fig. 2 is an enlarged sectional plan view of the same; Fig. 3 is a perspective view of the brush and the drawer removed from the brush and with the cover of the drawer in open position; and Fig. 4 is a perspective view of the razor strop.

The casing A is preferably made of 45 leather and is rectangular in shape, and from the back of the casing extends integrally a cover B adapted to pass over the open top of the casing to close the same, the front end of the cover B and the outer face of the front of the casing being provided 50 with fastening members C, C' for locking

the cover B when in closed position. Within the casing A are arranged sets of loops D, D', preferably of leather, and attached to the inner faces of the sides of the casing A, each set of loops extending in a transverse direction a distance below the open top of the casing A. The loops D are fashioned to receive and removably retain in vertical position a tooth brush E and a razor F, and the loops D' are fashioned to receive and to removably retain a vertically-disposed comb G and a pair of similarly-disposed scissors H. The tooth brush E is preferably provided with a removable guard E' to protect the bristles. The inner face of the back of the casing A is provided with a flat loop I extending from one side of the casing to the other side thereof, and this loop I is adapted to receive and retain a mirror J, preferably in the form of a polished plate 60 of aluminum or other metal. 70

It will be noticed that by arranging the loops D, D' and I in the manner described the several toilet articles mentioned are safely held in position and at the same time 80 sufficient space is left for the reception of a good-sized hair brush K. The hair brush K is preferably of the military style and is provided in its back with an opening K' extending from one side to the other so as 85 to form a convenient handle or a hand-hold to allow the user to firmly grip the back of the brush when it is intended to use the brush. Into the opening K' fits removably a drawer or a casing L, preferably 90 provided with a hinged cover L' and with partitions L² to divide the interior of the drawer L into different compartments for the individual reception of a shaving brush N, a stick of shaving soap O and a nail 95 brush P.

A razor strop Q in the form of a flexible band of leather, canvas or other suitable material is looped around the bristles of the brush K to protect the bristles against injury when placing the brush K into the casing A or removing it therefrom. It will be noticed that the loops D, D' and I and the toilet articles E, F, G, H and J carried by the said loops form projections inside of the 100 casing A and hence the bristles of the brush K would be liable to come in contact with the said projections and be injured by the same in placing the brush in position in the casing or removing it therefrom were it 105 110

not for the protecting band formed by the razor strop Q. The razor strop Q is provided at one end with a ring Q' and a fastening member Q², and the other end of the 5 razor strop is reduced in width to form a handle Q³ adapted to pass through the ring Q'. The strop handle Q³ is provided with a fastening member Q⁴ adapted to engage the fastening member Q² to fasten the ends 10 of the strop together after the strop is drawn tightly around the bristles of the brush K. The razor strop Q is somewhat wider than the length of the bristles of the brush K so that the strop also extends over 15 a portion of the sides and ends of the back of the brush and over the front and the rear of the drawer L to hold the latter against accidental displacement in the back of the brush K. By the user taking hold of the 20 ring Q' the razor strop Q and the brush K can be readily pulled out of the casing A whenever it is desired to use the brush and strop. After the strop and the brush are withdrawn from the casing the fastening 25 members Q² and Q⁴ are disengaged from each other to allow removal of the razor strop Q from the brush K. The ring Q' of the razor strop Q can now be engaged with a fixed hook, nail or other supporting 30 means (see Fig. 4) to allow of using the strop Q for stropping the razor F whenever it is desired to do so, it being understood that the razor F is removed from the corresponding loop D whenever it is desired to 35 strop and use the razor.

The drawer L is pushed out of the opening K' of the brush K whenever it is desired to use the brush or the contents of the drawer L.

40 The front of the casing A is preferably provided at the upper end with a cut-out portion to permit the user to readily re-

move the toilet articles from the casing A or place the same therein.

It will be noticed that by the arrangement 45 described a large number of toilet articles are safely mounted in the casing, which is exceedingly small in size, and ready access is had to the articles contained in the casing for removal of the articles whenever 50 it is desired to use the same for toilet purposes.

Having thus described my invention, I claim as new and desire to secure by Letters Patent:

55 1. A toilet case, comprising a casing, retaining devices on the inner walls of the said casing, toilet articles held removably in the said retaining devices, a brush held removably in the said casing, and a protecting band in the form of a razor strop and looped around the bristles of the said brush to protect the latter against the said retaining devices and the toilets articles carried thereby.

60 2. In a toilet case, the combination of a casing provided interiorly with retaining devices, a brush adapted to be placed into the casing between the said retaining devices, and a band in the form of a razor strop looped around the bristles of the brush to protect the same against contact with the 70 said retaining devices on placing the brush into the casing or removing it therefrom, the said band being provided at its ends 75 with fastening members to fasten the ends together.

In testimony whereof I have signed my name to this specification in the presence of two subscribing witnesses.

EDGAR PERCIVAL BIDWELL.
